UNITED STATES PATENT OFFICE.

JEFFERSON E. BARRETT, OF MOUNT VERNON, IOWA.

CAR-COUPING.

SPECIFICATION forming part of Letters Patent No. 254,260, dated February 28, 1882.

Application filed September 30, 1881. (No model.)

To all whom it may concern:

Be it known that I, JEFFERSON E. BARRETT, of Mount Vernon, in the county of Linn and State of Iowa, have invented a new and Improved Car-Coupling, of which the following is a specification.

The invention consists in a draw-head having a U-shaped groove in its upper surface, combined with a flat bar sliding in a vertical longitudinal slot in the draw-head, and provided with two lugs, which vertically-sliding bar has levers pivoted thereto for raising and lowering it, the free ends of these levers passing through slots in plates provided with locking devices; or the vertically-sliding bar can have a handle at its upper end, and can be locked in position by a pivoted latch on the top of the car. When the vertically-sliding bar is in the lowered position it holds the link 20 in the groove in the draw-head, and raises this link out of the groove in the draw-head when it (the vertically-sliding bar) is raised by means of the levers or the handle at its upper end.

The invention further consists in the construction and arrangement of parts and details, as will be more fully described herein-after.

Reference is to be had to the accompanying drawings, forming part of this specification, in which similar letters of reference indicate corresponding parts in all the figures.

Figure 1 is a perspective view of the end of a box-car provided with my improved car-coupling. Fig. 2 is a longitudinal sectional elevation of the ends of two cars provided with my improved car-coupling. Fig. 3 is a longitudinal elevation of the slotted plate with the locking-bar for locking the coupling-lever.

The draw-head A is provided with a U-shaped groove, A', in its upper surface, this groove being of the same size and formation as one-half of an ordinary car-coupling link, B, and the ends of this groove being at the front or outer end of this draw-head. The part A² of the draw-head between the shanks of the U-shaped groove is beveled upward and toward the inner end of the draw-head. At the rounded end of the groove A' the draw-head is provided with a longitudinal vertical slot, C, which extends across the rounded part

of the groove A'. A flat bar, D, adapted to slide in the slot C, is provided with two lugs, D' D', projecting toward the front of the draw-head A and forming a notch or recess, D². 55 This bar D is further provided with two horizontal and laterally-projecting flanges or lugs, D³, which are adapted to rest on the draw-head A when the bar D is in its lowest position. This bar D reaches up to the top of the 60 car H, and has a handle, E, at its upper end, and is guided by a slotted plate, E², projecting from the end of the car H, at the top of the same.

The bar D is provided on its rear or inner edge with a crook or bent arm, E³, through which crook and the bar D a pintle passes, which pivots the bar D to levers F F, extending in opposite directions from the bar D; but I may pivot these levers to the bars D in any 70 other suitable manner.

Each lever F is pivoted to a short bar, G, pivoted to a bracket, J, attached to the end of the car H, the free ends of each lever F passing through the vertical slot K near the outer edge of a flanged guide-plate, L, fastened to the end of the car near the side of the same by the flange in such a manner that this plate L projects from the end of the car parallel with the side of the car, as shown in Fig. 1. 80

To each plate L a flat bar, M, is pivoted above the top of the slot K, which flat bar M is provided with a series of lugs or teeth, N' N² N³, projecting from the edge toward the front or outer end of the draw-head, of which 85 teeth N² and N³ each have a notch or recess in the lower edge, the uppermost tooth, N', having a notch or recess both in the upper and lower edges. A handle-lug, O, projects from the flat side of each bar M near its lower end, 90 and the lower end, M', of each bar M is bent outward rectangularly.

A latch, P, having its ends beveled in opposite directions, and having catch and handle lugs P' P² at opposite ends and opposite edges, 95 is pivoted to the plate L in such a manner that this latch can hold the flat bar M in a raised position. A flat metal strip, Q, is secured at one end to the plate L, and serves as a guide for the lower or outer end of the flat bar M. 100 The flat bar D is provided at its upper end with a series of apertures, R R, adapted to re-

ceive a pin, S, near the end of a latch-lever, T, pivoted on the plate E², and provided with a vertical handle-lug, V.

The operation is as follows: The bar D of one car is so adjusted that the upper edge of its lower lug, D', will be below the upper surface of the draw-head A, as shown in dotted lines in the left-hand side of Fig. 2, and is locked in this position by passing the end of the corresponding lever, F, under the middle tooth, N², of the bar M. Then the link B is dropped into the groove A' and the lever F is released. The bar D drops by its own weight and holds the link in a horizontal position and projecting from the draw-head. The bar D need not be locked in this position, as its weight is sufficient to keep it in this position. Then the opposite draw-head is also adjusted in the manner shown in dotted lines in the left-hand side of Fig. 2. If the cars come together, the free end of the link B slides up the incline A² and drops onto the groove A'. Then the corresponding bar, D, is released and holds the link in the groove and prevents it from being thrown out by sudden shocks or jumps of the car. (See the right-hand side of Fig. 2.)

To uncouple the cars all that is necessary is to raise the bar D, as shown in full lines on the left-hand side of Fig. 2, whereby the link B will be raised out of the groove A', thus permitting it to be withdrawn from the draw-head.

The bar D may be operated by means of the levers F, or by means of the handle E at its upper end, and likewise the bar D can be locked in its various positions by means of pivoted latch T, or by means of the pivoted bars which lock the levers F. If the bar D is to remain unlocked, the bar M is swung in the inverse direction of the arrow a', and is locked in position by means of the latch P, as shown in Fig. 3, the lower bent end, M', of the bar M resting against the lug P' of the latch P. If this bar M is to be released, it is raised or swung in the inverse direction of the arrow a' a short distance, upon which the latch is turned in the position shown in dotted lines in Fig. 3. The lower end, M', of the bar M can now clear the lug P' of the latch P and drop back into the vertical position.

50 By means of the above-described car-cou-

pling device cars can be coupled and uncoupled without requiring the operator to pass in between the cars.

Having thus fully described my invention, I claim as new and desire to secure by Letters Patent—

1. The bar D, having two lugs, D' D', recess D², and flanges D³, in combination with a draw-head having the vertical slot C, as and for the purpose specified. 60

2. The bar D, having a bent arm, E³, connected by a pintle with the oppositely-extending levers F F, as shown and described.

3. In a car-coupling, the combination, with the draw-head A, provided with a U-shaped 65 groove, A', of the bar D, the levers F, the connecting-bars G, and the brackets J, projecting from the car H, substantially as herein shown and described, and for the purpose set forth.

4. In a car-coupling, the combination, with the draw-head A, of the bar D, the levers F, the plates L, each provided with a vertical slot, K, and of the pivoted bars M, provided with teeth N' N² N³, substantially as herein shown and described, and for the purpose set forth. 75

5. In a car-coupling, the combination, with the plate L, provided with a slot, K, of the pivoted bar M, provided with teeth N' N², &c., the guide-plate Q, and the latch P, substantially as herein shown and described, and for the purpose set forth. 80

6. In a car-coupling, the combination, with the plate L, provided with a slot, K, of the pivoted bar M, provided with a series of teeth, N' N², &c., and having its lower end, M', bent rectangularly, and of the pivoted latch P, provided with the lugs P' P² at the opposite ends, substantially as herein shown and described, and for the purpose set forth. 85

7. In a car-coupling, the combination, with the draw-head A, of the bar D, provided with a series of apertures, R, the slotted guide-plate E², the latch T, and the handle S, and the levers F, substantially as herein shown and described, and for the purpose set forth. 90
